UNITED STATES PATENT OFFICE.

JOHN WALTER GRANTLAND, OF CINCINNATI, OHIO.

LUBRICATOR.

1,152,020.

Specification of Letters Patent. Patented Aug. 31, 1915.

Application filed April 1, 1915. Serial No. 18,448.

To all whom it may concern:

Be it known that I, JOHN WALTER GRANTLAND, a citizen of the United States, and residing at Cincinnati, in the county of Hamilton and State of Ohio, have invented a new and useful Improvement in Lubricators, of which the following specification is a full disclosure.

The invention relates to lubricators and primarily to that class known as condensation displacement sight feed lubricators, principally used in connection with locomotives. In general, such type of lubricator comprises an oil reservoir, a condenser or steam condensing chamber located primarily at a higher elevation than the oil reservoir, a passage or conduit connecting the lower portion of the condenser with the lower portion of the oil reservoir, oil distributing passages either in the singular or plural number for delivering oil to distant points. The oil distributing passages connect with the oil reservoir through regulatable feed nozzles for discharging the oil in drops. The passages toward their lubricator discharge ends connect with the condenser through pressure equalizing tubes, and sight glasses axially located at the feed nozzle discharge end to observe the extent of oil feed.

A feature of the invention consists in providing a reservoir having its major portion approximately cylindrical with its axis extended horizontally, with the walls at its lower portion converging downward into flat surfaces forming a contracted sub-reservoir below the normal reservoir base. This sub-reservoir is divided by integral transverse partitions defining, in conjunction with the sub-reservoir walls, vertical conduits extending diametrically through the reservoir, each terminating with horizontal exit. These oil feed conduits are, throughout their entire length, exposed to the heated contents of the main and sub-reservoir, thereby maintaining the water within and oil passing through the conduit at a temperature assuring a free flow of the oil. The conduits provide an enlarged cross-sectional area and an unobstructed straight vertical passage, offering no interference to the upward trend of the oil drops in any angular position at which the lubricator may be disposed with the traveling plane of the locomotive.

Another feature of the invention relates to the mounting of sight feed features at the contracted portion of the reservoir and ex-

ternally thereof, so that the inner opposing lens ends will be approximately flush with the relative walls of the conduits, avoiding oil pockets, at such intercepting portion of the conduit and lenses, or obstruction to interfere with the oil feed.

Other features and advantages of the invention will be more fully set forth in the description of the accompanying drawing, forming a part of this specification, and in such drawings like characters of reference denote corresponding parts throughout the several views, of which:

Figure 1 is a central vertical section through a lubricator embodying my invention. Fig. 2 is a transverse vertical section on line 2—2, Fig. 1. Fig. 3 is a section on line 3—3, Fig. 1. Fig. 4 is a section on line 4—4, Fig. 1. Fig. 5 is a section on line 5—5, Fig. 1, illustrating only the reservoir.

In the lubricators of the class providing for a plurality of independent feeds and sight features, it has been found more practical to arrange the parts, so that the sight features extend in a horizontal plane, and adjacent each other, rendering it possible to have all sight feed features invisible from one, or opposite sides of the lubricator. In the double form it is of advantage to have the opposite observation glasses as close toward the feed nozzle spouts as possible, without forming any obstruction in the feed tube, giving a more clear sight.

The reservoir casing and glasses are subject at times to severe internal pressure and also to sudden changes in temperature, and, therefore, structurally must be capable to withstand such service. In practice, it has been found that the cylindrical type of reservoir casing is more practical to resist the strains.

The lubricator reservoir 1 comprises a cylindrical casing portion 2, having its axis extended horizontally. The lower portion thereof converges downwardly into flat surfaced vertical walls 3, forming a contracted sub-reservoir 4, see Fig. 4. The end of the cylindrical casing is provided with nipple openings for securing suitable fittings for filling and other purposes. The sub-cellular or sub-reservoir is divided by the integral transverse partitions forming walls for the respective vertical oil feed conduits 5, 6 and 7, which partitions together with the walls of the sub-reservoir continue upwardly to extend the feed tubes diametrically through

the cylindrical reservoir casing, each branching horizontally into extended discharge conduits 8 to which the different connections leading to the various parts to be lubricated 5 are connected. These horizontal branches 8 interiorly are provided with reducing plugs 9. A dome-shaped condenser 10 is fitted to the upper portions of the cylindrical casing and arranged to be connected with the engine 10 boiler for supplying steam thereto. The condenser interiorly has a series of equalizing tubes 11 vertically extended therein, connecting respectively at the upper portion 15 of the cylindrical casing with branch conduits 12 cast integral with the casing leading to respective oil feed tubes or conduits to equalize the pressure within the oil feed tubes. A valve-controlled by-pass 13 is formed within the reservoir casing, see Fig. 20, communicating with the lower portion or base of the condenser and through a tube 14 with the lower portion, or toward the normal base of the reservoir 1, providing a passage for the steam condensation from the 25 condenser into the reservoir to displace the oil.

15 represents an oil supply conduit extended vertically through the sub-reservoir and reservoir, and communicating with the 30 upper portion of the reservoir, and connecting with a horizontal supply conduit or chamber 16 at the base of the sub-reservoir, see Fig. 1. This oil supply chamber 16 connects through branch conduits or ports with 35 the various oil feed conduits 5, 6 and 7 of the series, and the control to each may be independent or in series to meet the various requirements. At the base of each oil feed tube, a feed nozzle 17 is provided and projected upwardly into the oil feed conduits and the supply to each controlled by a valve 18, secured to the base of the sub-reservoir. This disposes all of the feed regulating 40 valves in an adjacent position freely accessible from either side of the lubricator. Adjacent the discharge end of each of said drop feed nozzles 17 respectively, I provide oppositely disposed observation glasses 19, 19, see Fig. 2, which intercept the walls of 45 the conduits, each projecting into an aperture therewith to present the ends of the glasses substantially flush with the interior surfaces of the conduits. These glasses are socketed within the nipple extensions 20, 50 formed integral with the sub-reservoir walls and projecting externally thereof and screw threaded to receive a follower plug 21 for securely mounting the glasses in position. The lubricator is provided with the usual 55 drain ports and plugs or auxiliary feed outlets to meet the various requirements in their use.

60 The construction of feed nozzles, sight glasses, valves, etc., may be of any well-known construction, as they do not enter as

a factor to the features of the invention herein, and thus the different elements may be variously modified within the province of this invention. The operation is not changed and as this is well known in the art, it is 70 deemed not necessary to dwell thereon.

With my improved reservoir and integrally combined oil feed conduit structure, the efficiency of the lubricator is materially increased in that the oil has no opportunity 75 to cool in its passage through the conduits, for each of the conduits and the various supply branches all have surfaces exposed to the heated water or oil in the reservoir or sub-reservoir, thus at all times maintaining 80 the oil in a condition to flow freely. The feed conduits as arranged form a straight passage of an enlarged area in cross-section with no obstruction to interfere with the vertical trend of the oil drops, 85 assuring regularity of feed irrespective of whether or not the locomotive is running upon a lever or inclined track surface. All the detachable parts are easily accessible for removal, insertion or manipulation, compact 90 in arrangement, and very durable.

Having described my invention, I claim:—

1. In a lubricator device of the class described, a reservoir having its upper portion enlarged and extending axially horizontally, the reservoir walls downwardly converging and being projected below said enlarged portion, providing a reservoir extension of reduced area below the major reservoir, there being integral transverse partitions in said extension, defining in conjunction with the walls of said extension, a series of oil feed conduits within the reservoir base, said conduits being integrally extended upwardly and centrally through the 105 major portion of the reservoir to a series of horizontal outlets, one for each of the vertical conduits, an equalizing steam conduit for each horizontal outlet, a horizontal oil supply conduit in the base communicating 110 with the lower portions of said oil feed conduits and receiving oil from the major portion of the reservoir, drop feed devices in the base of said oil feed conduits, the walls of the reservoir base defining the lower portion of the oil feed conduits being apertured, and sight-feed features supported on the exterior walls of said reservoir extension adjacent said apertures, the lower portions 115 of the oil feed conduits defined by said partitions being in direct contact with the hot water condensation in said reduced reservoir extension.

2. In a condensation displacement lubricator, an oil reservoir casing having a cylindrical major portion, with its axis substantially in a horizontal plane, its walls at its lower portion converging downwardly into a contracted sub-reservoir, transverse partitions dividing said sub-reservoir casing, and 120

with the casing walls providing conduits continuing therefrom centrally through said cylindrical reservoir casing.

3. In a condensation displacement lubricator, an oil reservoir casing having a cylindrical major portion, with its axis substantially in a horizontal plane, its walls at its lower portion converging downwardly into a contracted sub-reservoir, transverse partitions dividing said sub-reservoir casing, and with the casing walls providing conduits continuing therefrom centrally through said

cylindrical reservoir casing, and observation glasses having a horizontal axis supported upon opposite sides of said sub-reservoir casing, and external of the reservoir.

15 In witness whereof, I hereunto subscribe my name, as attested by the two subscribing witnesses.

JOHN WALTER GRANTLAND.
